UNITED STATES PATENT OFFICE

90,784

DESIGN FOR A BOTTLE OPENER

Oscar A. Sinner and John B. Sinner, San Diego, Calif.

Application June 12, 1933. Serial No. 48,385

Term of patent 3½ years

To all whom it may concern:

Be it known that we, OSCAR A. SINNER and JOHN B. SINNER, citizens of the United States and residents of San Diego, county of San Diego, State of California, have invented a new, original, and ornamental Design for a Bottle Opener, of which the following is a specification, reference being had to the accompanying drawing, forming a part thereof.

We claim:

The ornamental design for a bottle opener, substantially as shown.

Signed at Los Angeles, California, June 6, 1933.

OSCAR A. SINNER.
JOHN B. SINNER.
